UNITED STATES PATENT OFFICE.

WILLIAM H. PIKE, JR., OF ST. LOUIS, MISSOURI, ASSIGNOR, BY DIRECT AND MESNE ASSIGNMENTS, TO PIKE ADDING MACHINE COMPANY, OF ST. LOUIS, MISSOURI, A CORPORATION OF MISSOURI.

RIBBON-FEEDING MECHANISM FOR TYPE-WRITING MACHINES.

SPECIFICATION forming part of Letters Patent No. 738,935, dated September 15, 1903.

Application filed November 21, 1902. Serial No. 132,300. (No model.)

To all whom it may concern:

Be it known that I, WILLIAM H. PIKE, Jr., a citizen of the United States, residing at St. Louis, Missouri, have invented certain new and useful Improvements in Ribbon-Feeding Mechanism for Type-Printing Machines, of which the following is a specification.

This invention relates to ribbon-feeding mechanism for type-printing machines; and the object of the invention is to provide means by which the ribbon may be kept under constant tension and which will automatically reverse the feed of the ribbon when either spool ceases to rotate, as will be fully described hereinafter, reference being had to the accompanying drawings, in which—

Figure 1 is a plan view of the ribbon-feeding mechanism and a portion of a platen. Fig. 2 is a side elevation of Fig. 1. Fig. 3 is an end view of Fig. 2 looking in the direction of the arrow.

The ribbon-spools 608^R and 608^L are mounted at different heights at the outer sides of two separated side plates 500^R and 500^L, respectively, the ribbon being guided by two quarter-turned rolls 655 across the printing-line above the platen 880, and the rolls 655 being mounted in brackets 614, secured to the side plates. Means are provided for frictionally resisting the rotation of the spools, the lower spool being attached to a shaft 646 and the other mounted on a stud 640, which turns in a bushing 641, fixed to the plate 500^L, and this stud has on its inner end a nut 642, and between the nut and the plate 500^L is a flat spring 643, a steel disk or washer 644, and a fiber washer 645, the washer providing a non-abrading friction-surface. The steel disk and spring are constructed to turn with the stud, and the nut is used to set up a suitable tension on the spring, and thus frictionally restrain the movement of the stud, and so prevent the spool from overrunning. Similar parts create a frictional resistance to the shaft 646 and its spool. Each spool is provided with a reversing device P, in which is a ratchet-wheel 685, connected with the adjacent spool, and a pawl which may be automatically thrown into and out of engage-

ment with the ratchet. A lever consisting of separated plates 601 and 602, connected by studs or rivets, oscillates about the axis of each ratchet-wheel, and between the plates is a pawl 676, Fig. 2, in position to engage the ratchet-wheel. Each pawl is supported on a movable pivot 632, guided in slots 632^b in the plates 601 and 602. The pivot is normally held in either extreme position by a spring 634^a, which presses inward a rod 634, having a stud 633, guided by slots 633^a in the plates 601 and 602, and a link 632^a connects each stud 633 to the pivot-stud 632, which carries the pawl.

The ratchet-wheels 685 of the two reversing devices P have their teeth facing in opposite directions, and the pawl-pivots 632 are connected by a link 603, which keeps the pivots at a uniform distance from each other and secures the harmonious but alternate action of the pawls. The two reversing-levers are connected by a link 604, and an arm 600 on the inner lever-plate 601, is connected by a link 613 to an arm 902 on a rock-shaft 922. The slots 632^b in the plates 601 and 602, which guide the pawl-pivot studs, are preferably of 75 the angular form shown, with the ends equally distant from the center of the ratchet-wheels and the apex of the angle at a greater distance. The link 603, connecting the pawl-pivot studs is of a length proper to position 80 the pawl-pivots the same distance apart as the centers of the ratchet-wheels. Only one pawl is in position to engage its ratchet-wheel at a time, and the working pawl is held in position by the action of the spring 634^a on 85 the rod 634. With the working pawl in position the other pawl is held away by the action of the spring holding the pivot, one end of the slot with the pawl lifted and held out of contact with the ratchet by a stud or pin 90 630, suitably placed in the plate 602, to be engaged by the tail 676^a of the pawl.

A ribbon is placed on one spool and conducted through the guides and attached to the other spool. Assuming the working pawl 95 to be the one coacting with the ratchet-wheel adjacent to the lower spool when the machine is operated, causing the main rock-

shaft 922 to oscillate, the link 613, connected to the plate 601, will oscillate the lever, and thereby cause the pawl to turn the ratchet-wheel and spool step by step, thereby winding the ribbon on it against the friction applied to the other spool. This tension results in keeping the ribbon taut. When the ribbon is all wound off one spool, the ribbon will become so taut that the spools will not turn, and the ratchets thereof remain practically stationary. When the pawl adjacent to the full spool on the next movement engages the ratchet thereof, said pawl, as it cannot turn the ratchet nor swing with the oscillating lever, will remain relatively stationary, and as the lever swings down the pivot of the said pawl slides to the other end of the slot 632^b, and the pawl by contact with the stud 630 is thrown out of engagement with its ratchet, and the connected pawl is thrown into engagement with the ratchet of the empty spool and begins to turn the latter.

The plates 500^R and 500^L may be supported upon the machine in any suitable manner and may serve as supports for other parts of the machine.

Without limiting myself to the details of construction illustrated and described, I claim—

30 1. In a ribbon-feeding mechanism, the combination of two rotary spools independently supported to turn about stationary axes, means for alternately and positively rotating said spools, and means whereby either spool when in a fixed position resists the movement of one of the parts to thereby shift the operating means into action on the other spool, substantially as set forth.

2. In a ribbon-feeding mechanism, the combination of two rotary spools independently supported to turn about stationary axes, independent means for rotating the respective spools, a connection between said rotating means acting to hold one of said rotating

45 means in operative relation with its spool when the other is out of operative relation with its spool, and means operated from either spool when in a fixed position for moving the said connection to change the relative positions of the two rotating means, substantially as set forth.

3. The combination of the ribbon, two spools

to which the ends of the ribbon are connected, a ratchet connected with each spool, a lever and pawl for engaging each ratchet supported on a movable pivot, and means for throwing the pawl out of action when the spool becomes stationary and thereby throwing the connected pawl into action on the other spool, substantially as set forth. 60

4. The combination of the ribbon, two spools to which the ends of the ribbon are connected, a ratchet connected with each spool, a lever and pawl for engaging each ratchet supported on a movable pivot, means for throwing either pawl out of action when the adjacent spool is stationary, and connections between the pawls to shift them into and out of action alternately, substantially as set forth. 65

5. In a ribbon-feed mechanism, the combination of two rotary spools independently supported, a ratchet-wheel connected to each spool, levers carrying pawls for operating the spools, a movable pivot for each pawl, a link connecting said pivots and holding one pawl 70 in operative relation to its wheel and the other pawl out of operative relation to its wheel, and means for operating the oscillating frames, substantially as set forth. 75

6. In a ribbon-feeding mechanism, two spools supported for independent rotation, a ratchet-wheel connected to each spool and the teeth of one of said ratchet-wheels facing oppositely to those of the other, levers supported to oscillate about the axes of the 85 wheels, a movable pivot carried with each lever, a pawl connected to each pivot and adapted to engage the adjacent ratchet-wheel, a link connecting said pivots whereby one pawl is in engagement with its wheel when the other is out of engagement with its wheel, springs engaging said pawls, and means for oscillating said frames, and for shifting the relative position of the pawls when either wheel ceases to rotate, substantially as set 90 forth. 95

In testimony whereof I have signed my name to this specification in the presence of two subscribing witnesses.
